UNITED STATES PATENT OFFICE.

ROBERT T. ABELL, OF CLEVELAND, OHIO, ASSIGNOR OF TWO-THIRDS TO
WESLEY ROYCE AND JOHN H. FRANCIS, BOTH OF SAME PLACE.

STEAM-ENGINE.

SPECIFICATION forming part of Letters Patent No. 403,714, dated May 21, 1889.

Application filed November 26, 1888. Serial No. 291,834. (No model.)

To all whom it may concern:

Be it known that I, ROBERT T. ABELL, of Cleveland, in the county of Cuyahoga and State of Ohio, have invented certain new and

5 useful Improvements in Steam-Engines; and

I do hereby declare the following to be a full, clear, and exact description of the invention, such as will enable others skilled in the art to which it pertains to make and use the same.

10 My invention relates to improvements in a steam-engine having oscillating piston; and it consists in certain features of construction and in combination of parts, hereinafter described, and pointed out in the claims.

15 In the accompanying drawings, Figures 1 and 2 are end elevations, the former being enlarged and partly in section. Fig. 3 is an isometric view in detail corresponding in scale with Fig. 1.

20 The steam-cylinder consists of outer and inner concentric rims, respectively, A and A', and head A², integral with these rims, and a removable head, B, each head having a central hub projecting outward, and in the bore 25 of these hubs are journaled, respectively, rock-shafts C C'. These shafts, at the inner ends thereof, either abut or come in close proximity to each other. On the inner ends of these shafts are mounted, respectively, disks C' C',

30 each disk, on the inner face thereof, having laterally-projecting lugs c c, the lugs of the two disks interlocking, but having play enough between them circumferentially to accommodate the reverse oscillations of the 35 two shafts. Each lug c is recessed on the face thereof in a radial direction to receive a radial arm, c', the arrangement being such that the two sets of arms all operate in the same or central plane of the cylinder. These arms

40 extend through and operate in slots a' of the inner rim, A'. The outer ends of these arms are slightly conical and fit in corresponding seats in the respective pistons D D', the outer ends of each arm being screw-threaded and

45 provided with nut c², to hold the piston firmly to its seat on the arm, the pistons on the outer periphery thereof having recesses that admit the nuts below the surface of the pistons. It

50 will be observed that two pistons, D, are attached to the same set of arms and are located diametrically opposite each other, while

the pistons D' are mounted on the other set of arms and are located in the same relative position to each other, and consequently the two pistons of a set balance each other perfectly.

The pistons of small engines may be solid; but for larger engines they should be cored or chambered to lighten them, the ends of the pistons being all that necessarily fit the cylinder, and any suitable packing may be used to secure tight joints with the cylinder at the ends of the pistons.

Shafts C, outside their journal-bearings, are provided with rock-arms E, and these arms

65 are connected by pitmen e with cranks F, the latter being mounted on the respective ends of shaft F' and extending in opposite directions from the shaft. This shaft is provided with a fly-wheel and with a band-wheel, or

70 whatever may be necessary to transmit the power of the engine. The cylinder is provided with the same number of cylindrical steam-chambers a as there are pistons—in the present instance four—these steam-chambers

75 being located, respectively, opposite the points of the main cylinder where opposing piston ends nearest approach each other, as shown, with ports a² connecting each steam-chamber with the main cylinder, each steam-chamber,

80 of course, having induction and eduction pipes a³ and a⁴. Each steam-chamber is provided with an oscillating valve, G, of ordinary construction, one such valve being shown at the top in Fig. 1. As heretofore, the one trun-

85 nion of each oscillating valve extends through a suitable stuffing-box in the removable head of the steam-chamber, such trunnion having attached an arm, g, and each arm g being connected by a link, g', with a disk, H, the latter

90 being mounted loose on the shaft C, that projects from this side of the engine. Disk H is connected by eccentric-rods h with eccentric h', the latter being mounted on shaft F'. The valves are given the necessary lead to cushion

95 the opposing ends of the pistons as they come in close proximity to each other, and the valves have suitable lap, more or less, according as it is desired to use steam more or less expansively. While two opposite valves—for

100 instance, the valves at top and bottom—are admitting steam the valves located on the

side are exhausting steam, and vice versa, all of which will be readily understood by persons skilled in the art. As the axes of the steam-chambers are parallel with the axis of the main cylinder, these chambers need not be separated but a short distance from the bore of the main cylinder, by reason of which the ports, although of ample width and extending the full length of the cylinder, may be so short in a radial direction that it requires but little steam to fill the port, and consequently the waste steam from such cause may be reduced to a minimum. The perfect balance attained with this engine adapts it to high speed without tendency to shake or vibrate. The engine may be arranged to have the valves on the quarters, instead of at top, bottom, and sides, if so preferred.

With this variety of engine four pistons are preferable to two, for the reason that two pistons would not balance each other, except by means of the connection with the crank-shaft. The engine may be constructed with six, eight, or more pistons, if for any reason it were found advantageous to do so.

What I claim is—

1. The combination, with a steam-cylinder composed of two concentric circular rims and heads, of rock-shafts, arms secured thereon and passing through the inner rim, and pistons secured on the ends of the arms.

2. The combination, with a steam-cylinder consisting of two concentric circular rims and

heads secured against the outer edges of the rims, of segmental pistons arranged in series, the pistons of one series operating between the pistons of the other series, each series of pistons being mounted on a rock-shaft independent of the rock-shaft of the other series, but having a common axial line, substantially as set forth.

3. The combination, with a steam-cylinder composed of two concentric circular rims and heads secured against the outer edges of the rims, of segmental pistons located between the rims and arranged in series, the pistons of one series operating between the pistons of the other series, rock-shafts, arms passing through the inner rim and connecting the pistons and rock-shafts, and a rock-arm mounted on each rock-shaft, the said rock-arms being connected by pitmen with a crank-shaft, substantially as set forth.

4. The combination, with a steam-cylinder and segmental operating-pistons arranged in two series and operating in said cylinder, of a series of steam-chambers and a valve in each chamber, substantially as set forth.

In testimony whereof I sign this specification, in the presence of two witnesses, this 24th day of October, 1888.

ROBERT T. ABELL.
